UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO

FEED-LIMIT DEVICE FOR MANIFOLD STRIPS

Application filed October 23, 1929. Serial No. 401,745.

This invention relates to improvements in mechanisms for feeding strips in predetermined lengths, being specifically adapted for feeding record strips for use in auto-
5 graphic registers and the like.

It is a general object of the invention to provide an improved arrangement whereby successive predetermined lengths of a strip or the like may be measured.

10 Another object is to provide an improved arrangement for feeding forwardly successive predetermined lengths of an autographic record strip or the like, the lengths corresponding ordinarily to lengths of blank forms or recording areas on the strips.

20 A further object is to provide an improved strip feed limiting device or gauge for intermittently limiting strip feed to predetermined lengths whereby predetermined strip lengths may be severed.

25 A further object is to provide an improved gauge or strip feed limiting device which may be automatically set or returned to initial position after an operative action thereof.

30 Other objects will be in part pointed out in connection with the following detailed description of an illustrative embodiment of the invention, and will be in part obvious in connection therewith.

35 The invention accordingly comprises the features of construction, combinations of elements, and arrangement of parts, which will be exemplified in the construction hereinafter set forth and the scope of the application of which will be indicated in the claims.

40 For a complete understanding of the nature and objects of the invention, reference is made to the following detailed description of an illustrative but preferred embodiment of the invention, and to the accompanying drawings, in which

45 Figure 1 is a central, vertical, longitudinal section through a manifolding machine or autographic register embodying the invention;

50 Fig. 2 is a top plan view thereof, the carbon sheet supports being omitted and parts

being broken away for clearness of disclosure;

Fig. 3 is a partial sectional view on the line 3—3 of Fig. 1 looking toward the right;

Fig. 4 is a partial sectional view on the line 4—4 of Fig. 4 looking toward the left, and

Fig. 5 is a plan of one of the record strips.

Referring to the drawing for a detailed description of the embodiment of the invention there illustrated, a casing 10 of any desired construction may be formed with an interior compartment for reception of a supply pad 11 shown in dot and dash lines, Fig. 1, which may be loaded into the compartment through a door 12 preferably pivotally mounted to swing about one edge as shown. The supply pad or pack may be of any desired form but is preferably of the zigzag type in which one or two or more long strips 13 are interfolded zigzag so as to form leaves between successive folds, and the folds being preferably weakened as by perforations 14 on transverse lines to facilitate severance of the leaves. One or more of the record strips 13 are preferably provided with blank forms 15 arranged in a series therealong to facilitate the reception of an inscription which may be entered manually or otherwise. The strip which is to receive the original inscription will be provided with these blank forms and the other strip or strips may also be similarly provided.

80 The record strips 13 may be guided from the storage supply through a slot 16 in a top plate 17 which may as shown form a writing table or platen for supporting the record strips in position for reception of an inscription. For supporting the strips upon the platen and guiding them in their feeding movement, a transverse bar or plate 18 may be positioned adjacent one end of the platen and spaced thereabove, and a similar bar 19 may be provided adjacent the opposite end of the platen.

85 If it is desired to transfer an inscribed record to a record strip, a transfer sheet 20 such as carbon paper may be supported in position over the platen. A carbon supply

roll 21 is shown as supported at one side of the plate, the sheet 20 extending therefrom transversely over the platen between adjacent record sheets and supported at the opposite side of the platen by a holding device such as the clamp 22 shown in Fig. 3.

The platen 17 may be longitudinally inclined as shown and an inclined plate 23 is mounted therebeneath for longitudinal sliding movement. This sliding plate or slide 10 functions as a gauge or measuring device for measuring the length of record strips to be fed forwardly in order to bring successive blank forms into inscription receiving position on the platen and for facilitating stopping the strips in correct position. The gauge 23 is mounted for longitudinal sliding movement by means of supporting slide-ways formed by slide plates 24 mounted 15 beneath the platen, and is provided at the rear or lower end with a downturned flange 25 and at its upper or forward end with an upturned flange 26. Stop lugs 27 project inwardly from the upper ends of the slide-ways 24 being positioned to contact with the 20 ends of the downturned flange 25 to limit the gauge to a predetermined forward travel as indicated in dot and dash lines of Fig. 1. Movement of the gauge in the opposite direction 30 may be limited by the upper flange 26 coming into contact with the forward edge of the platen plate as in full lines, Fig. 1. It will be seen that the travel of the gauge plate is thus limited to a predetermined amount 35 which may correspond to the length of each record leaf having one of the blank forms 15.

For returning the gauge plate automatically to initial position after having been drawn forwardly as described, the plate may be of sufficient weight to cause it to slide by gravity from its forward position to retracted position; for this purpose if necessary, a weight 28 may be attached to the gauge 45 plate.

To facilitate manually gripping the record sheets at their forward ends against the gauge plate, a deep notch 29 is formed in the forward edge of the platen plate 17, and a 50 less deep notch 30 is formed in the coincident underlying edge of the gauge plate opening through the flange 26 thereof. This arrangement provides a margin 31 on the gauge plate exposed through the deep notch 29 against which the forward ends of the strip may be manually gripped when the gauge and strips are to be moved forwardly.

The upturned flange 26 may also function as an abutment for the forward ends of the 60 record strip in order that the latter may be initially correctly positioned relatively to the platen and to the gauge plate.

The manner of operating the improved feed limit device will now be apparent.

When the strips 13 are properly positioned

by abutting the forward edges thereof against the flange 26 as shown in Fig. 1 and a record has been inscribed, the forward edge of the strips are then manually gripped against the gripping surface 31 and the gauge plate and strips pulled forwardly together. This forward feeding movement of the strips is checked by the lugs 27, the strips being then in correct position with the next successive blank form upon the 70 writing surface of the platen. Upon release of the gauge plate by the operator, it automatically returns by gravity to its initial position. Release of the gauge plate without releasing the hold upon the strips is 80 facilitated at this point by means of the notch 30 in the gauge plate since the forward edges of the strips overlap said notch. The forwardly fed inscribed parts of the record strip may then be severed as desired and the device is ready for the reception of another inscription.

It will be observed that the forward edge of the bar 19 may serve as a tearing edge for severing the strips. Since this edge is 90 positioned adjacent to the gripping surface 31 and the notches 29 and 30, being spaced slightly thereabove, the free severed edges and adjacent margins at the forward ends of the strips lying on the platen will lie in 95 position to be gripped by the thumb or finger as soon as they fall into position after a severing operation. The forward margins of the strips are thus always positioned for gripping engagement with the gauge plate 100 so they may be gripped and pulled forwardly with the latter.

Since certain changes may be made in the above construction and different embodiments of the invention could be made without departing from the scope thereof, it is intended that all matter contained in the above description or shown in the accompanying drawing shall be interpreted as 105 illustrative and not in a limiting sense. 110

Having described my invention, what I claim as new and desire to secure by Letters Patent is:

1. In an autographic register, in combination, an inclined platen upon which a record strip may be fed from a supply source and supported for inscription, and a movable gauge member slidably mounted adjacent said inclined platen and adapted to advance with said strip so as to determine a 115 desired advancement thereof, said gauge member being weighted to return it to initial position by gravity.

2. In an autographic register, in combination, a platen upon which a record strip may be fed from a supply source and supported for inscription, and a slidably mounted strip feed limiting plate underlying said platen and having a gripping surface exposed adjacent the forward part of said platen 125 130

against which the record strip may be manually gripped so as to advance with said strip limiting plate, said plate also having a notch disposed at its forward edge adjacent its gripping surface to facilitate release of said plate while retaining grip of said strip whereby said plate may be returned to initial position.

5. In an autographic register, in combination, a platen upon which a record strip may be fed from a supply source and supported for inscription, a strip feed limiting plate slidably mounted in inclined position underlying said platen and having a gripping surface exposed adjacent the forward part of the platen against which the record strip may be manually gripped so as to advance with said strip feed limiting plate, said plate also having a notch in its forward edge adjacent said gripping surface to facilitate release of said plate while retaining grip upon said strip, and said plate being weighted to automatically return it to initial position after advancement thereof.

25. In an autographic register, in combination, a platen upon which a record strip may be fed from a supply source and supported for inscription, a longitudinally inclined slidably mounted gauge plate underlying said platen and having a gripping surface exposed adjacent the forward part of said platen against which the record strip may be manually gripped so as to advance with said gauge plate, said plate also having a notch disposed at its forward edge adjacent its gripping surface to facilitate release of said plate while retaining grip of said strip whereby said plate may be returned to initial position, means for limiting forward advancement of said gauge plate, and gravity means for automatically returning said plate after advancement thereof.

40. In an autographic register, in combination, a platen upon which a record strip may be fed from a supply source and supported for inscription, a slidably mounted strip feed gauge plate underlying said platen and having a gripping surface exposed adjacent the forward part of said platen against which the record strip may be manually gripped so as to advance with said gauge plate, said plate also having a notch disposed at its forward edge adjacent its gripping surface to facilitate release of said plate while retaining grip of said strip whereby said platen may be returned to initial position, and an upturned flange at the forward edge of said gauge plate through which said notch opens, said flange forming an abutment ledge for the forward edge of the record strip and cooperating to stop the plate in retracted position.

45. In an autographic register, in combination, a casing having a storage compartment for a supply of traveler record strip, a

platen over which said strip may be fed for reception of an inscription, and a gauge plate mounted adjacent said platen for forward travel with the strip to determine advancement of the latter, said gauge plate having a notch in the forward edge thereof and being provided with a forward abutment for the edges of the record strip.

5. In an autographic register, in combination, a casing having a storage compartment for a supply of traveler record strip, a longitudinally inclined platen over which the strip may be fed for reception of an inscription, and a gauge slidably mounted in inclined position adjacent the platen for advancement with the record strip, said gauge being weighted for automatic return after an advancement thereof.

7. In an autographic register, in combination, a platen upon which a record strip may be fed from a supply source and supported for inscription, a gauge plate mounted for forward movement adjacent said platen and having a manual gripping surface exposed adjacent the forward part of said platen against which the record strip may be gripped manually so as to advance with said gauge plate, said plate also having a notch disposed at its forward edge adjacent its gripping surface, and strip severing means positioned so as to sever the strip with its forward margin overlapping said gripping surface and notch in position to be manually gripped against said surface.

8. In an autographic register, in combination, a platen upon which a record strip may be fed from a supply source and supported for inscription, a forwardly movable strip feed limiting plate mounted adjacent said platen and having a manual gripping surface exposed adjacent the forward part of said platen against which the strip may be manually gripped so as to advance with said strip feed limiting plate, and a strip severing edge positioned adjacent to said gripping surface but spaced thereabove so that the forward margins of the strips as severed by said edge are positioned for manual gripping downwardly against said gripping surface.

9. In an autographic register, in combination, a platen upon which a record strip may be fed from a supply source and supported for inscription, a strip feed limiting plate mounted for forward movement adjacent said platen, said limiting plate having an upwardly exposed gripping surface positioned to lie adjacent the strip and against which the strip may be gripped manually and advanced with said plate, and means for limiting the advancement of said plate so as to limit strip feed to predetermined lengths.

10. In an autographic register, in combination, a platen upon which a traveler
